(57) **CLAIM**

The ornamental design for an earphone charging system, substantially as shown and described.

DESCRIPTION

FIG. 1 is a top isometric view of an earphone charging system, showing our new design.

FIG. 2 is a bottom isometric view thereof.

FIG. 3 is a top plan view thereof.

FIG. 4 is a bottom plan view thereof.

FIG. 5 is a left side elevational view thereof.

FIG. 6 is a right side elevational view thereof.

FIG. 7 is a front elevational view thereof; and,

FIG. 8 is a rear elevational view thereof.

(Continued)

The broken lines in the figures depict portions of the article
which form no part of the claimed design.
